UNITED STATES PATENT OFFICE.

WILLIAM J. MILLER, OF SWISSVALE BOROUGH, PENNSYLVANIA.

PRESSING-PLUNGER MECHANISM.

1,326,365.

Specification of Letters Patent. Patented Dec. 30, 1919.

Original application filed August 11, 1917, Serial No. 185,647. Divided and this application filed June 22, 1918. Serial No. 241,481.

To all whom it may concern:

Be it known that I, WILLIAM J. MILLER, a citizen of the United States, and residing in the borough of Swissvale, in the county 5 of Allegheny and State of Pennsylvania, have invented or discovered new and useful Improvements in Pressing-Plunger Mechanism, of which the following is a specification.

10 This patent application is a division of my previously filed patent application Serial Number 185,647, filed August 11, 1917.

My present invention consists in certain new and useful improvements in pressing 15 plungers for machines for the manufacture of pressed glass articles.

More particularly, my present invention comprises means for mounting the plunger in the machine in such a manner that it 20 may be adjusted and alined so as to properly center it with the mold, or molds as the latter are presented in the forming or pressing position.

In the accompanying drawings, which are 25 merely intended to illustrate the principles of my invention without limiting the scope of the same to the construction shown, Figure 1 is a broken elevation of the pressing mechanism of a machine, the same being 30 partially sectional to show the parts; Fig. 2 is an enlarged detail of the same with the plunger omitted, and Fig. 3 is a horizontal section along the line III—III in Fig. 1.

The following is a detailed description 35 of the drawings:

B and C represent a pair of upright standards which form part of the general machine not shown in full.

N represents a cross head slidingly 40 mounted on said standards and upon which the pressing plunger P is mounted. To indicate generally the application of power to raise and lower said cross head in the pressing operations, I have shown toggle 45 links 176, but it will be understood that any means for depressing and elevating the plunger support or mounting may be used.

The cross head N is provided with a transverse, horizontal opening 178, and 179 is a 50 circular hole extending down from the top of said cross head into the opening 178. 180 is a threaded shaft extending down through said hole and having its lower end screwed into a threaded hole 178^a in the 55 floor of the opening 178. 181 is a cross bar

adjustably fixed on the upper end of the shaft 180 by means of upper and lower locking nuts 182.

The outer ends of the bar 181 are provided with vertical holes for the downward extension of the headed bolts 183 which extend down through the cylindrical sleeves 184 which slide in vertical cylindrical bearings 185 in the cross head N. The lower threaded ends of the bolts are screwed into 65 threaded holes in the spring plate O, thus supporting said spring plate.

The upper ends of the sleeves 184 are countersunk, as shown, to seat the lower ends of the helical springs 186 which are 70 coiled about the bolts 183 and bear against the cross bar 181, thus tending to resiliently depress the spring plate O below the cross head N.

187 is a horizontal yoke adjustably supported on the shaft 180 by means of the screw collar 188. 189 represents a pair of gripping fingers, pivoted at their upper ends to the extremities of the yoke 187 and depending through slots 190 in the bottom 80 of the opening 178. The lower ends of said fingers are provided with inwardly extending hooks which fit under and engage the beveled top flange 191 of the pressing plunger P, thus supporting said plunger in 85 place.

Q is a ring provided with radial handles 192 and internal cam surfaces 193. The ring is rotatably supported below the cross head N by means of depending hooked hangers 90 194 which permit the ring to be shifted laterally. Thus the ring Q may be said to be floatably supported from the cross head. The ring Q encircles the upper end of the pressing plunger and suspension fingers. 95 By turning the ring in the proper direction, the cam surfaces 193 force and lock the fingers in snug and rigid supporting engagement with the beveled flange 191 of the plunger. By screwing up the collar 188 on 100 the shaft 180, thus elevating the yoke 187, the upper end of the pressing plunger P is forced up against the bottom surface of the cross head N, thus rigidly connecting the plunger with the cross head.

The plunger may be adjusted laterally or horizontally in relation to the cross head by shifting the ring Q before the collar 188 is screwed up to clamp the plunger against the cross head. The plunger may be read- 110

justed in relation to the cross head by screwing the collar 188 down on the shaft 180 and the ring Q and the plunger P may then be shifted, as desired.

5 A rotation of the ring in the direction reverse to that above referred to releases the fingers 189 and permits the detachment of the plunger.

Before the machine is put into operation 10 for the manufacture of glass articles, a mold is centered under the pressing mechanism and the proper plunger is mounted and adjusted so that it will properly enter the mold when depressed. By means of the 15 mechanism for mounting and adjusting the plunger just described, any irregularity or lack of alinement in the various elements, such as between the mold table and the pressing mechanism may be corrected.

20 The office of the spring plate O is to resiliently engage the mold top and seat itself thereon as the plunger is depressed into the mold, and to lag behind the rising plunger to steady the mold and its contents and to 25 strip the glass from the emerging plunger.

What I desire to claim is as follows—

1. In a machine for pressing articles of glass, a plunger mechanism consisting of a sliding support horizontally disposed and 30 provided with vertical slots through the same, fingers with hooked lower ends pivotally mounted on said support and depending through said slots, a pressing plunger having its head provided with a perimetral shoulder adapted to be secured to the under 35 surface of said support, and an annular locking member rotatably mounted against the under surface of said support and provided with internal cam surfaces adapted 40 to engage the lower ends of said fingers and clamp the same into engagement with said shoulder.

2. In a machine for pressing articles of glass, a plunger mechanism consisting of a sliding support horizontally disposed and 45 provided with vertical slots through the same, fingers with hooked lower ends pivotally mounted on said support and depending through said slots, a pressing plunger having its head provided with a perimetral shoulder adapted to be secured to the under 50 surface of said support, an annular locking member rotatably mounted against the under surface of said support and provided with internal cam surfaces to engage the 55 lower ends of said fingers and clamp the same into engagement with said shoulder, and means for shifting said member laterally to properly aline said plunger.

60 3. In a machine for pressing articles of glass, a plunger mechanism consisting of a sliding support horizontally disposed and 65 provided with vertical slots through the same, fingers with hooked lower ends pivotally mounted on said support and depend-

ing through said slots, a pressing plunger having its head provided with a perimetral shoulder adapted to be secured against the under surface of said support, an annular locking member rotatably mounted against 70 the under surface of said support and provided with internal cam surfaces adapted to engage the lower ends of said fingers and clamp them into engagement with said shoulder, and means for raising said fingers 75 relative to said support to tighten the plunger against said support.

4. In a machine for pressing articles of glass, a plunger mechanism consisting of a sliding support horizontally disposed and 80 provided with vertical slots through the same, fingers with hooked lower ends pivotally mounted on said support and depending through said slots, a pressing plunger provided with a perimetral shoulder 85 adapted to be secured to the under surface of said support, an annular locking member rotatably mounted against the under surface of said support and provided with internal cam surfaces adapted to engage the 90 lower ends of said fingers and clamp the same into engagement with said shoulder, means for shifting said member laterally to properly aline said plunger, and means for raising said fingers relative to said support to tighten the plunger against said support. 95

5. In a machine for pressing articles of glass, a plunger mechanism consisting of a sliding support horizontally disposed, a member mounted on said support and adjustable vertically in relation thereto, fingers with hooked lower ends pivotally depending from said member, a pressing plunger having its head provided with a perimetral shoulder adapted to be secured to the under surface of said support, and a locking ring rotatably mounted against the under surface of said support and provided with internal cam surfaces adapted to engage the lower ends of said fingers and clamp them in engagement with said shoulder. 100

6. In a machine for pressing articles of glass, a plunger mechanism consisting of a sliding support horizontally disposed, a member mounted on said support and adjustable vertically in relation thereto, fingers with hooked lower ends pivotally depending from said member, a pressing plunger having its head provided with a perimetral shoulder adapted to be secured to the under surface of said support, a locking ring rotatably mounted against the under surface of said support and provided with internal cam surfaces adapted to engage the lower ends of said fingers and clamp them into engagement with said shoulder, and means for shifting said ring laterally to properly aline said plunger. 115 120 125 130

7. In a machine for pressing articles of glass, a plunger mechanism consisting of a sliding support horizontally disposed, a shaft extending upwardly from said support, a yoke adjustably mounted on said shaft, fingers with hooked lower ends pivotally depending from said yoke, a pressing plunger having its head provided with a perimetral shoulder adapted to be secured to the under surface of said support, and a locking ring rotatably secured to the under surface of said support and provided with internal cam surfaces adapted to engage the lower ends of said fingers and clamp them into engagement with said shoulder.

8. In a machine for pressing articles of glass, a plunger mechanism consisting of a sliding support horizontally disposed, a

shaft extending upwardly from said support, a yoke adjustably mounted on said shaft, fingers with hooked lower ends pivotally depending from said yoke, a pressing plunger having its head provided with a perimetral shoulder adapted to be secured to the under surface of said support, 20
